LINE CASTING MACHINE

Lewis Geisert, Philadelphia, Pa.

Application November 3, 1934, Serial No. 751,398

1 Claim. (Cl. 199—27)

This invention relates to improvements in the assembler mechanisms of line-casting machines.

Considerable difficulty has been experienced in machines of this class due to a tendency of the 5 matrices to foul or check at the point where the matrices are transferred to the assembling elevator, with resultant transpositions or clogging. This tendency arises from a faulty construction which permits slight wear of the parts or looseness in the assembling elevator to cause a gap 10 between the assembler chute block and the elevator in which the thinner matrices may become caught. To rectify this, it is necessary under the prior construction to remove the block and to pier 15 out the rail at the juncture to an extent again affording a close joint between the block and the elevator. The defective construction referred to has, over a long period of time, caused considerable trouble, loss of time and defective work.

Specifically, therefore, a principal object of my invention is to improve the structure of this portion of the mechanism overcoming the aforesaid difficulty.

More specifically, an object of the invention is 25 to provide adjustable means for maintaining a desirably close joint between the assembler chute block and the assembling elevator operative in both assembling levels to preclude defective feeding of the matrices to the elevator.

In the attached drawing:

Figure 1 is a side elevational and partial sectional view of the lower portion of the assembler chute and the immediately related portions of 35 the assembling elevator of a line-casting machine;

Fig. 2 is a fragmentary transverse sectional view taken on the line 2—2, Fig. 1;

Fig. 3 is a view in perspective of the assembler block; and

Fig. 4 is a perspective and partial sectional view of the aforesaid immediately related part of the assembling elevator.

With reference to Fig. 1 of the drawing, 1 indicates the entrance of the assembler chute, and 45 2 is the matrix belt which delivers the matrices to the rails of the assembler chute block 3. Towards its lower end, the block 3 is provided with the usual star wheel 4, which in known manner delivers the matrices 5 to the assembling eleva- 50 tor 6.

The lower ends of the rails 7, 7 of the block 3 in a normal assembly should lie in close proximity to the entering ends of the lower rails 8, 8, of the assembling elevator and also to the end of the 55 adjustable duplex rail 9 which forms the upper

assembling level, the ends of the elevator rails 8 and 9 being provided with upstanding matrix-retaining flanges formed either integrally with the rails, as indicated at 10 and 11, or by a separate plate. In the illustrated mechanism, provision in the form of a tapped hole 12 is made for securing a retaining plate of this character at the end of the lower front rail 8, the plate being removed in the drawing for the purpose of clarifying the structure shown. When the juncture of the rails of the block 3 and of the elevator 6 is not close, a condition that frequently prevails as a result of wear or by reason of inaccuracies of construction or looseness of the related parts, the thin matrices tend to catch in the gap with the results set forth above. The excessive enlargement of the gap at the rail junctures due to wear is particularly prevalent in those assemblies wherein a slight offset in alignment between the assembler block and the assembling elevator mechanism is provided for the purpose of preventing the entering matrices from damaging the working faces of the matrices already in the elevator, since in this type of construction the wear is concentrated on that rail of the assembler block 20 which extends to the ends of the lower front rail 25 and the overlying duplex rail of the elevator.

In accordance with my invention and in assemblies of the last-named type, I form the lower end of that one of the rails 7 of the block 3 which receives the excessive wear as a separate element which may be advanced by adjustment into close proximity to or engagement with the ends of lower front and duplex rails of the elevator. In the present instance, this element takes the form of a substantially rectangular plate 13 which fits slidably within a recess at the lower end of the rail proper. The plate 13 preferably is beveled at its inner upper corner, as indicated at 14, and at the rear is provided with a longitudinal slot 15 for reception of the screw 16 which secures the plate to the block 3. The plate 13 may be made of any suitable material, and I prefer to employ vulcanized fibre which has been found exceptionally well suited for the purpose. As previously set forth and as illustrated in Fig. 1, the plate 13 is of sufficient depth to embrace at its forward edge both the ends of the lower front rail 8 of the elevator and the duplex rail 11.

It will be apparent that with an adjustable device of this character the requirement for an original close fit between the block 3 and the elevator 6 need not be as critical as in the prior devices where no adjustment feature was provided. It will be noted further that any gap originally 50 55

existing between the lower end of the rail 7 and the rails 8 and 11 of the elevator may be readily compensated by simple adjustment of the plate 13; and that any wear upon the elements tending to form a gap may be compensated by a similar simple adjustment. The device while a simple one eliminates a major defect of the prior construction which has been responsible for considerable trouble and losses due to defective assembling of the matrices and to repair expenses.

It will be apparent that the same principle may be applied to maintain a close juncture between the inner rail 7 of the block and the inner lower rail 8 of the elevator where this may be found necessary in order to insure proper delivery of the matrices to the elevator. It will further be apparent that there may be modifications of the illustrated embodiment without departure from the invention.

I claim:

In a line-casting machine, the combination with an assembling elevator comprising matrix-supporting rails, of an assembler chute for delivering matrices to said elevator, said chute comprising an assembler block having matrix-guiding rails, the lower ends of which are arranged in proximity to the rails of said elevator, means providing a slot at the lower end of a rail of said block, and a plate mounted in said slot with an end thereof in alignment with said rail, said plate in effect constituting the lower end of the rail and being adjustable in the slot to maintain a close juncture between said rail and the entering end of the adjoining rail of said elevator.

LEWIS GEISERT.
